PORTABLE WIRE TYING MACHINE

Léon Malinge, Nantes, France

Application August 15, 1935, Serial No. 36,367
In France February 25, 1935

8 Claims. (Cl. 140—93)

This invention relates to wire tying machines of the well known type comprising chiefly wire-clamping means, wire-tensioning means, wire-twisting means and wire-cutting means mounted 5 on a common frame capable of being laid on the bale or other package to be tied by the wire.

The primary object of the invention is to provide a portable machine of this type of a much more simplified structure and much cheaper construction than similar machines made heretofore while being capable of perfectly tensioning and twisting a wire of any gauge and of any cross sectional shape with the utmost rapidity.

A further object of the invention is to provide 15 a portable machine of the above type wherein all parts are easily dismountable and replaceable relative to the frame whereby any part can be removed and replaced by a new one when it is worn out or when it does not properly work on 20 any particular wire.

A still further object of the invention is to provide a portable machine of the above type wherein the frame is made up of independent parts held together by simple means such as bolts and 25 nuts and capable therefore of being dismantled almost instantaneously to gain access to the interior and change the wire twisting or holding means for instance for substituting such a means for twisting a wire of any given size for a similar 30 means which was used for twisting a wire of another given size.

Still a further object of the invention is to provide 35 a portable machine of the above type wherein the parts of which the frame is made up can be manufactured and assembled in series, for instance die cast and bolted to one another and then fitted with the wire working means without requiring skilled labor.

With these and such other objects in view as 40 will incidentally appear hereinafter, the invention comprises the novel construction, arrangement and combination of parts that will now be described with reference to the accompanying diagrammatic drawings showing suitable constructional embodiments of the same and forming a part of the present disclosure.

In the drawings:

Fig. 1 is an elevational view of a machine according to the invention.

Fig. 2 is a top plan view of this machine.

Fig. 3 is a cross sectional view on the line III—III of Fig. 1.

Fig. 4 is a cross sectional view on the line IV—IV of Fig. 1.

Fig. 5 is an elevational view of another machine according to the invention.

Fig. 6 is a top plan view of the machine shown in Fig. 5.

Fig. 7 is a cross sectional view on the line VII—VII of Fig. 6.

Fig. 8 is a cross sectional view on the line VIII—VIII of Fig. 6.

Fig. 9 is a cross sectional view on the line IX—IX of Fig. 6.

Fig. 10 is an elevational view, partly broken away, of another machine according to the invention.

Fig. 11 is a top plan view of the machine shown in Fig. 10.

Fig. 12 is a cross sectional view on the line XII—XII of Fig. 11.

Fig. 13 is a cross sectional view on the line XIII—XIII of Fig. 11.

Fig. 14 is a cross sectional view on the line XIV—XIV of Fig. 11.

Like reference characters denote like parts throughout the several views.

Reference being first had to the machine shown in Figures 1 to 4 inclusive, it will be seen that 25 the frame of this machine comprises primarily a dished end plate 1 having a base 2 formed with an outwardly flaring notch 3 and an outwardly extending wing 4. The machine frame also comprises a casing 5 open at both ends of 30 a shape or cross outline matching that of the plate 1 and having a base 6 notched at 7 to correspond to the notch 3. The machine frame still comprises another dished end plate 8 provided with an outwardly extending wing 9. The 35 plates 1, 8 and the casing 5 define an enclosure when brought together.

The end plates 1 and 8 are provided with holes (three in the embodiment illustrated) through which bolts 10, 11, 12 can be engaged. Such 40 bolts are fitted with outer nuts 13, 13', 14, 14' and 15, 15' which, when tightened, hold the parts 1, 5, 8 firmly together, as shown in Figures 1 and 2.

In view of this built-up construction of the 45 frame of the machine, said frame can be dismantled almost instantaneously. Another advantage is that the parts 1, 5, 8 can be produced very easily, for instance die cast, any suitable metal or alloy such as brass being utilizable.

The wing 4 on the left hand end plate 1 has a hole receiving a rigid core 16, made for instance of steel, which is held therein by a set screw 17. The core 16 carries a small anvil 18 projecting from one of its faces. In an eccentric hole 50 55

formed in the core 16 is revolubly fitted a boss 19 the periphery of which is knurled or otherwise roughened, as shown at 19a. The eccentered boss 19 carries a hand lever 20 clamped thereto by a screw 21 and nut 22.

5 By rotating the hand lever 20 clockwise or anti-clockwise, the boss 19 can be moved away or towards the anvil 18 for releasing or clamping the end of the wire, as will be described hereafter.

10 The end frame plate 1 has a pair of holes through which are journalled the ends of a pair of shafts 23, 24 the opposite ends of which are journalled in corresponding holes formed in the end frame plate 8.

15 The shaft 23 extends outside the right hand side of the machine frame and is carried by a bearing 25 forming an extension of the wing 9 of the end plate 8. The free end of the shaft 23 removably carries a handle 26 clamped by a 20 threaded pin 27. A small pinion 28 is fast on the shaft 23 inside the frame casing 5.

The shaft 24 carries a pinion 29 meshing with the pinion 28 and with another pinion 30 the body and hub of which protrude on both sides of its 25 teeth. This pinion 30 has a deep radial notch 31 of flaring outline extending through its toothed part hub and body as in the type of wire tensioning and twisting machines which the invention is improving. The purpose of said pinion 30 is 30 to twist the two lengths of wire received in its notch 31 so as to produce a pair of wire twists or knots on both sides on said pinion. The notch 31 much coincide with the notch 7 of the casing 5 so that the two lengths of wire may be readily 35 inserted thereinto preparatory to the twisting operation.

The casing 5 is fitted with a wire guide 32 having a flaring notch registering with its notch 7 as shown in Fig. 4 and adapted to receive the 40 two strands of wire and to prevent them from overlapping while they are being subjected to the twisting stress by the notched pinion 30. The wire guide 32 may be held in position by any known means such as screws and may be replaced by another when it becomes worn out 45 or when a wire guide having a notch of a given size must be substituted for a wire guide having a notch of another size.

On the bolt 12 is pivotally mounted inside the 50 hollow-end plate 8 and substantially at right angles to said bolt a small elongated steel plate 33 having a nick 33a in its lower edge. The latter is sharpened adjacent said nick to permit the plate 33 to act as a cutter or knife for cutting off 55 one strand of the wire while the other strand is received in the nick 33a and thus protected from being cut, as will be described hereinafter. To the knife 33 is anchored one end of a spring 34 anchored at its opposite end to a pin 35 carried 60 by the frame plate 8. The pivotal motion of the knife 33 across the wire guide 32 takes place against the action of the spring 34. The upper edge of the knife 33 has such an outline as to cooperate with a toothed-shaped cam 36 fixed to, 65 or formed on, the shaft 24. Owing to this arrangement, at each revolution of the shaft 24, the cam 36 depresses the knife 33 against the action of the spring 34, and the knife cuts off the outer strand of the wire while the inner wire strand is protected in the nick 33a, as aforesaid.

70 The outwardly extending wing 9 of the end frame plate 8 carries a stud 37 fitted with a hand lever 38. The stud 37 carries at one end a wire-tensioning wheel 39 having spaced cuts 39a in its periphery and at its opposite end a ratchet

wheel 40. A pawl 40a anchored to a peg 40c is associated with the ratchet wheel 40. The cuts or indentations 39a in the tensioning wheel 39 are adapted to receive a bight of the strand of wire to which a tensioning stress must be applied.

The operation of this machine is as follows: When it is desired to tie or encircle a bale or a similar package with wire, the machine is laid or crawled on any face of said bale and one end of a wire of suitable size is inserted between the 10 anvil 18 and the boss 19 of the wire-clamping means, whereupon by rotating the hand lever 20 anti-clockwise said end of the wire is clamped between the anvil 18 and the knurled groove 19a of the boss 19. The wire is then passed through the 15 notch 31 of the twisting pinion and through the notch in the wire guide 32 and bent around the bale to be tied, and again passed into said two notches which thus receive two strands of the wire. The end of the wire opposite to the one 20 clamped between 18 and 19 is passed through two or more indentations 39a of the wire-tensioning wheel 39 and the hand lever 38 is imparted a reciprocating motion so as to rotate the wheel 39 in the proper direction for tensioning the wire, a 25 rotation in the reverse direction being prevented by the ratchet wheel 40 and pawl 40a. By then rotating the handle 26 clockwise, the gear 28, 29 transmits its rotation to the twisting pinion 30 which produces two knots or twists of wire on 30 either sides of said pinion. The cam 36 carried by the shaft 24 then comes into engagement with the upper edge of the knife 33 and depresses the latter against the action of the spring 34, which cuts the outer strand of wire, as above-stated. 35 By then rotating the hand lever 20 clock-wise, the end of the wire may be released and the machine taken off the bale which is now positively and permanently tied or encircled with wire.

Reference being now had to the modified machine shown in Figures 5 to 9 inclusive, it will be seen that the general construction is the same as in the constructional form shown in Figures 1 to 4, the corresponding parts being designated by like reference numerals.

The constructional differences may be described as follows: The frame casing interposed between the side plates 1 and 8 is made up of two parts 5, 5' having bases 6, 6' and juxtaposed side by side and held together removably by the bolts 11, 12, 13. The shafts 23 carrying the handle 26 is fitted with a pinion 28 of the same size as the pinion 29 fitted on the shaft 24 and meshing with the smaller twisting pinion 30, so that one revolution of the handle 26 in the direction disclosed by the arrows e, f, g is sufficient for performing the wire-twisting operation, as aforesaid.

The arrows a, b show in what respective directions the hand lever 20 must be rotated for clamping or releasing the end of the wire located between the small anvil 18 and the boss 19. The arrows c, d show in what respective directions the hand lever 38 must be rotated for rotating the tensioning wheel 39 under the control of the ratchet wheel 40.

In this constructional form, two knives 33, 41 are pivotally mounted on the bolt 12. These two knives are situated on opposite sides of the notched twisting pinion 30 and are adapted to cut the ends of the two strands of wire intermediate the twists or knots formed by said pinion and the tensioning wheel 39 and clamp 18, 19 respectively, on completion of the twisting operation, as aforesaid. Small coil springs 34, 42 are associated with the respective knives 33, 41 to

lift them back to inoperative positions immediately after the cutting operation. The shaft 24 carries a pair of cams 36, 43 so located as to timely engage the upper edges of the knives 33, 41 and depress them into cutting positions.

Reference being now had to the further modified machine shown in Figures 10 to 14 inclusive, it will again be seen that the general construction is the same as in the two constructional forms described above, the corresponding parts being designated by like reference numerals.

The constructional differences may be described as follows: The pinion 28 fitted on the shaft 23 carrying the handle 26 meshes with a twice smaller pinion 29a fitted on the shaft 24 carrying the pinion 29 which meshes with the twisting pinion 30. The gearing ratio of the gear 28, 29, 29a is such that it is sufficient to impart half a revolution to the handle 26 as shown by the arrows *h, i, j* and by the interrupted line *k* (Fig. 14) to perform the wire-twisting operation. Therefore the machine is specially adapted for use where one or more complete revolutions could not be imparted to the handle 26, for instance when encircling with wire bales or similar packages of very large size.

For the sake of easier manipulation of the machine, there is provided a bail 46 having parallel legs 44, 45 formed with holes engaged over the ends of the bolt 10 and held by the clamping nuts 13. The legs of the bail 46 might also be held by the bolts 10, 12 simultaneously.

As illustrated, the shaft 23 projects outside the side plate 8 only to a small extent so that the handle 26 does not protrude much outside the overall outline of the machine, which is thus rendered still less cumbersome than in the two other constructional forms as above described.

The pawl or dog 40a is held in permanent engagement with the teeth of the ratchet wheel 40 by a small coil spring 40b abutted against the outer face of the side piece 8.

From the foregoing description, it will be seen that whatever the constructional form of the machine according to the invention may be, the objects of the latter are accomplished since the structure of said machine is extremely simple, its dismantling merely requires disengagement of the bolts 10, 11, 12 and all operative parts of the machine can be easily replaced by others when required, either for accommodating a wire of another cross sectional size or for another purpose incidental to the use of the machine. For instance the notched twisting pinion 30 may be easily taken off the casing 5 or 5, 5' and replaced by another pinion having a notch of another size capable of receiving a wire of a different cross section. The knives 33, 41 may be replaced by others very easily. Dismantling the machine, substituting one or several parts for others and re-erecting the machine into operative condition only requires one or two minutes and can be performed without requiring skilled labor, by the user of the machine himself. A cheap set of spare parts can be supplied to the user by the manufacturer.

It is obvious that those skilled in the art may vary the details of construction without departing from the spirit of the invention which, therefore, must not be regarded as limited to the above disclosure except as may be required by the claims.

What is claimed is:

1. In a wire tying machine of the type specified, the combination of a frame casing having a notched base, a pair of end plates of a shape

matching that of the casing, each plate having an outward wing, bolts extending through the end plates and casing for removably holding them together, shafts journaled in said plates, wire-clamping means on the wing of one end plate, 5 wire-tensioning means on the wing of the other end plate, a notched wire twister revoluble in the casing adjacent its notch, gear elements on the shafts for rotating said twister, an actuator on one of the shafts, a knife pivoted to one of the 10 bolts, and a cam on one of the shafts to move the knife to wire-cutting position responsive to motion of the actuator.

2. In a wire tying machine of the type specified, the combination of a frame casing open at both ends and having a notched base, a pair of end plates of a shape matching that of the casing, each plate having an outward wing, bolts extending through the end plates and casing for removably holding them together, shafts journaled in said plates, wire-clamping means on the wing of one end plate, wire-tensioning means on the wing of the other end plate, a notched wire twister revoluble in the casing adjacent its notch, gear elements on the shafts for rotating said 20 twister, an actuator on one of the shafts, a pair of knives pivoted on one of the bolts and located on either sides of the wire twister, and a pair of cams on one of the shafts to move the knives to wire-cutting positions responsive to motion of the 25 actuator.

3. In a wire tying machine of the type specified, the combination of a frame casing open at both ends and having a base formed with an outwardly flaring notch, a pair of end plates of 35 a cross outline matching that of the casing, each plate having an outward wing, bolts extending through the end plates and casing for removably holding them juxtaposed side by side, shafts journaled in said plates, wire-tensioning means on 40 the wing of one end plate, a notched wire twister revoluble in the casing adjacent its notch, gear elements on the shafts for rotating said twister, a handle on one of the shafts, wire-cutting means pivoted to one of the bolts, cam means on one of 45 the shafts to move the wire-cutting means to operative position responsive to actuation of the handle, a core fitted in the wing of the other end plate, a wire-receiving anvil in said core, and a boss revoluble eccentrically in said core and provided with a hand lever whose pivotal motion in the one or the other direction moves the periphery of the boss towards or away from the anvil into wire-clamping or releasing position.

4. In a wire tying machine of the type specified, the combination of a frame casing open at both ends and having a notched base, a pair of dished end plates of a cross outline matching that of the casing, each end plate having an outward wing, tie bolts extending through the end 60 plates and casing and fitted with nuts outside the end plates for removably holding together the casing and plates, shafts journaled in said plates, wire-tensioning ratchet means on the wing of one end plate, a notched wire twisting pinion revoluble in the casing adjacent its notch, gear elements on the shafts for rotating said pinion, a handle on one of the shafts, spring-urged wire-cutting means pivoted to one of the bolts, cam means on one of the shafts to move the wire-cutting means to operative position responsive to actuation of the handle, a core fitted in the wing of the other end plate, a wire-receiving anvil secured to the periphery of said core, and a circular boss having a grooved and roughened pe- 75

- riphery, said boss being revoluble eccentrically in said core and provided with a hand lever whose pivotal motion in the one or the other direction moves the periphery of the boss towards or away from the anvil into wire-clamping or wire-releasing position.
5. In a wire tying machine of the type specified, the combination of a frame casing open at both ends and having a notched base, a pair of dished end plates of a cross outline matching that of the casing, each plate having an outward wing, one of the plates having a notched base matching that of the casing, tie bolts extending through the end plates and casing and fitted with nuts outside the end plates for removably holding the casing and plates juxtaposed side by side to define an enclosure, shafts journalled in said end plates, wire-clamping means on the wing of the end plate having a notched base,
- 10 20
- 15 25
- 20 25
- 25 30
- 30 35
- 35 40
- 40 45
- 45 50
5. In a wire tying machine of the type specified, the combination of a frame casing open at both ends and having a notched base, a pair of dished end plates of a cross outline matching that of the casing, each plate having an outward wing, one of the plates having a notched base matching that of the casing, tie bolts extending through the end plates and casing and fitted with nuts outside the end plates for removably holding the casing and end plates side by side to define an enclosure, shafts journalled in said end plates, wire-clamping means on the wing of the end plate having a notched base, wire-tensioning means on the wing of the other end plate, a notched wire twister revoluble in the casing adjacent its notch, a wire guide stationary in the casing and having a notch aligned with the casing notch, gear elements on the shafts for rotating said twister, a handle on one of the shafts, wire-cutting means pivoted to one of the bolts, and cam means on one of the shafts to move said cutting means to operative position responsive to actuation of the handle.
6. In a wire tying machine of the type specified, the combination of a two-part frame casing open at both ends and having a notched base, a pair of dished end plates of a cross outline matching that of the casing, each plate having an outward wing one face of which is aligned with one face of the casing to form a continuous unobstructed bearing surface, one of the end plates having a notched base matching that of the casing, tie bolts extending through the end plates and intermediate casing and fitted with nuts outside the end plates for removably holding the casing and plates side by side to define an enclosure, shafts journalled in said end plates, wire-clamping means on the wing of the end plate having a notched base, a ratchet-braked indented wire-tensioning wheel on the wing of the other end plate, wire-twisting means removably supported in the casing adjacent its notch, gear elements on the shafts for actuating said wire-twisting means, an actuator on one of the shafts, wire-cutting means pivoted to one of the bolts, and

cam means on one of the shafts to move said cutting means to operative position responsive to motion of the actuator.

7. In a wire tying machine of the type specified, the combination of a frame casing open at both ends and having a base formed with an outwardly flaring notch opening sidewise, a pair of dished end plates of a cross outline matching that of the casing, each plate having an outward wing and one face aligned with a corresponding face of the casing, one of the end plates having a base formed with a notch aligned with the casing notch, tie bolts extending through the end plates and intermediate casing and fitted with nuts outside the end plates for removably holding the casing and end plates side by side to define an enclosure, shafts journalled in said end plates, wire-clamping means on the wing of the end plate having a notched base, wire-tensioning means on the wing of the other end plate, a notched wire twister revoluble in the casing adjacent its notch, gear elements on the shafts for rotating said twister, a handle on one of the shafts, a pair of knives pivoted to one of the bolts and located on either side of the wire twister, the cutting edge of each knife being so shaped as to engage only one strand of wire, and a pair of cams on one of the shafts to move the knives to wire-cutting positions responsive to motion of the actuator.

8. In a wire tying machine of the type specified, the combination of a frame casing open at both ends and having a projecting base defining an outwardly flaring notch opening sidewise, a pair of dished end plates of a cross outline matching that of the casing, each plate having an outward wing, tie bolts extending through the end plates and casing for removably holding them together to define an enclosure, shafts journalled in said plates, wire-clamping means on the wing of one plate, wire-tensioning means on the wing of the other end plate, a notched wire twister revoluble in the casing adjacent its notch, intermeshing gear elements on the shafts for rotating said twister, a bail held outside the casing by at least one bolt, an actuator carried by one of the shafts, wire-cutting means pivoted to one of the bolts, and cam means on one of the shafts to move said cutting means into operative position responsive to motion of the actuator.

LÉON MALINGE.
